ALBERT H. DE VOE, OF WESTFIELD, NEW JERSEY, ASSIGNOR TO THE SINGER MANUFACTURING COMPANY, A CORPORATION OF NEW JERSEY.

EDGE-GUIDE.

1,313,275.

Specification of Letters Patent.

Patented Aug. 19, 1919.

Application filed September 16, 1916. Serial No. 120,443.

To all whom it may concern:

Be it known that I, ALBERT H. DE VOE, a citizen of the United States, residing at Westfield, in the county of Union and State 5 of New Jersey, have invented certain new and useful Improvements in Edge-Guides, of which the following is a specification, reference being had therein to the accompanying drawings.

10 This invention relates to sewing machines and particularly to attachments for the cloth-plates thereof.

It has for its object to provide a new and improved cover-slide closing the opening 15 in the cloth-plate through which access is had to the under thread mechanism, and to combine therewith, an edge-guide of small dimensions affording very little obstruction to the passage of fabric and particularly 20 useful in glove sewing, in which blanks, shaped to conform to the fingers, must be laid on both sides of the edge-guide in performing certain stitch attaching operations. It is also desirable that the cover- 25 plate and edge-guide carried thereby be readily replaceable by a cover-slide without an edge-guide in order that the machine may be available for general use. The fastening means for securing the cover-slide in 30 position facilitates removal of the cover-plate.

To the attainment of these ends, the cloth-plate is provided with an opening bridged by a relatively narrow throat-plate of the 35 usual form, and to either side thereof are arranged cover-plates or slides with beveled edges fitted to undercut guideways along the sides of the opening in the cloth-plate. For securing the cover-slide in operative 40 position, a lever with a beveled end or cam-face is pivoted to the upper face of the cover-slide, and is normally spring-pressed in a direction tending to force said cam-face against the guideways in the cloth-plate, 45 through the agency of a straight spring secured at one end to the lever laterally of its pivot and bearing against a stop or abutment fixed to the cover-slide. Beneath the cover-slide, in a substantially rectangular- 50 shaped recess, is secured the body portion of an edge-guide whose active fabric-guiding portion consists of an offset portion bent upwardly at a right angle and undercut so as to overhang the throat-plate with

which the cover-slide is abutted when in 55 normal operative position.

The invention consists further in certain features of construction which will appear in the following detailed description of the accompanying drawings, in which— 60

Figures 1 and 2 are plan views of the top and bottom respectively of the cover-slide and guide; and Fig. 3 is a cross section on the line A—B Fig. 1, showing the combined cover-slide and guide in end elevation. Fig. 65 4 is a detail view in side elevation of the edge-guide.

The cloth-plate 1 has a raised portion 2 in which is provided an opening, indicated generally at 3, bridged by a throat-plate 4 70 of suitable form having an elongated needle-hole 5 therein. Cover-plates 6 and 7 are arranged flush with the throat-plate on opposite sides thereof and the edges 8 and 9 are beveled to fit undercut guideways 10 formed 75 along the sides of the opening 3 in the cloth-plate.

A lever 11 is pivoted at 12 to the upper face of the cover-slide or slide 7 adjacent an abutment or stop 13 fixed to the cover-slide and a spring 14, fixed at 15 to the lever adjacent the pivot 12, bears against the abutment 13 with such force as to rotate the lever about its pivot, thereby forcing the beveled end 16, formed by a downwardly bent portion of one end of the lever, into engagement with the undercut guideway 10, whereby the cover-slide is urged in a direction transverse to the guideways with sufficient force to be held wedged in place. The cover-slide 80 is cut away at 17 to receive the beveled end 16 of the lever and the side walls 18 and 19 of the incision constitute stops limiting the movement of the lever in either direction as is obvious from the drawings. For effecting the release of the beveled end or cam-face 16 and removal of the cover-slide or slide, the lever 11 at its other end is bent upwardly to form a finger-grip 20 and a clip 21, similarly bent to form a finger-grip and 95 fixed to the cover-slide adjacent the grip-end of the lever, facilitates manipulation of the lever.

The cover-slide is recessed at 22 and the body portion or shank 23 of an edge-guide, 105 indicated generally at 24, is received therein. An active fabric edge-guiding portion 25 is struck up from the blank laterally of

the body portion as shown clearly in Fig. 4 of the drawings. This active edge-guiding portion is highest at its forward end adjacent the needle-hole in the throat-plate. 5 Its top is beveled at 26 and slopes down to a point where it disappears beneath a U-shaped slot in the cover-plate. The edge-guide is also undercut at 27 so as to overhang the throat-plate and to bring the active 10 edge-guiding portion in close proximity to the needle. The edge-guide 24 may be adjusted on the cover-plate to vary the location of the seam through the agency of a clamp-screw 28 tapped into the body 23 15 of the edge-guide and slot 29 in the cover-plate.

The cover-plate 6 is frictionally retained in position by the flared spring end 30 conveniently formed by a short saw-cut as obvious 20 from the drawings.

It will be apparent from the foregoing description that I have devised means for securing the combined cover-plate and edge-guide in operative position on the cloth-plate of the machine, which means firmly hold the edge-guide against the thrust of the fabric as it is pulled along by the feed, but which are easily manipulated to permit small adjustments of the edge-guide or complete 25 removal of the cover-plate. In certain classes of work it is desirable to quickly set the edge-guide at slightly different distances from the needle in order to change the distance of the line of stitches from the raw 30 edge of the material. For this purpose the lever 11 may be readily moved to unlock and shift the cover-slide the required distance with an inconsiderable waste of the operator's time.

40 Having thus set forth the nature of the invention what I claim herein is:—

1. In a sewing machine, a cloth-plate having an opening therein, guideways along the sides of said opening, in combination with 45 a cover-plate removably secured in said guideways, and an edge-guide having a body portion secured to the under side of said cover-plate and an active fabric edge-guiding portion at an angle thereto and extending upwardly above the upper surface of the cover-plate.

50 2. In a sewing machine, a cloth-plate having a raised portion provided with guideways adjacent an opening therein, in combination with a cover-plate carrying an edge-guide and means frictionally retaining said cover-plate in position in said guideways.

55 3. In a sewing machine, a cloth-plate having an opening therein, parallel guideways along the sides of said opening, in combination with a cover-plate fitted to said guideways and carrying an edge-guide, and means on the cover-plate tending to force said cover-plate in a direction transverse to said guideways whereby said cover-plate may

be held wedged in operative position, said means being movable to a position between the sides of the cover-plate whereby the introduction and removal of the cover-plate is facilitated.

70 4. In a sewing machine, a cloth-plate having an opening therein, guideways along the sides of said opening, in combination with a cover-plate fitted to said guideways, and means tending to force said cover-plate in a direction transverse to said guideways whereby said cover-plate may be held wedged in operative position, said means including an arm pivoted to the cover-plate and having a cam-face, and a spring arranged to force said cam-face toward a line passing through the pivot of said arm and perpendicular to the guideways.

75 5. In a sewing machine, a cloth-plate having an opening therein, guideways along the sides of said opening, in combination with a cover-plate fitted to said guideways and means tending to move said cover-plate in a direction transverse to said guideways whereby said cover-plate may be held wedged in operative position, said means including a lever pivoted intermediate its ends and having at one end a cam-face, a spring arranged to force said cam-face against the guideway, and a clip fixed to said cover-plate adjacent the other end of said lever for facilitating manipulation thereof to effect release of the cover-plate.

80 6. A sewing machine with a cloth-plate having an opening therein, a throat-plate bridging the opening, in combination with a cover-slide removably secured to said cloth-plate flush with said throat-plate, an edge-guide secured to said cover-slide and having an active fabric-guiding portion extending above the upper surface of said cover-slide and overhanging said throat-plate adjacent the stitching point.

85 7. In a sewing machine, a cloth-plate having an opening therein, a throat-plate bridging the opening and having a needle-hole therein, in combination with a cover-slide removably secured to said cloth-plate, an edge-guide, the major portion of which is secured beneath said cover-slide and the smaller active fabric-guiding portion of which projects above the cover-plate, and means permitting adjustment of said edge-guide on the cover-slide when in its operative position adjacent the needle-hole in the throat-plate.

90 115 120 125 130 8. A cover-plate, an edge-guide carried thereby, said cover-plate having a recess in its lower face, said cover-plate being provided with a slot, a screw passing through said slot and adjustably securing said edge-guide in said recess and being accessible from the upper face of the cloth-plate, and means for moving said cover-plate lengthwise.

9. In a sewing machine, a cloth-plate having an opening therein, a throat-plate bridging the opening and having a needle-hole therein, in combination with a cover-slide 5 removably secured to said cloth-plate, an edge-guide the major portion of which is secured beneath said cover-slide and a smaller active fabric-guiding portion of which projects above the cover-plate in 10 proximity to the needle hole, and means for moving said cover-slide to adjust said edge-guide toward or away from the throat-plate.
10. In a sewing machine a removable cover-plate provided with a slot, an edge 15 guide having a shank positioned beneath said plate and an active edge-guiding portion projecting above the upper surface of

said cover-plate, and a screw passing down through said slot and securing said shank adjustably to said cover-plate, said screw 20 affording means for adjusting said edge-guide accessible from above the cover-plate.

11. In a sewing machine, a cloth-plate provided with an opening and guide-ways along the sides thereof, in combination with 25 a cover-plate, and means automatically operating to wedge the plate in the guide-ways and manually operative to release said plate whereby it may be readily moved in the guide-ways, said means including a spring- 30 pressed lever.

In testimony whereof, I have signed my name to this specification.

ALBERT H. DE VOE.
